UNITED STATES PATENT OFFICE

WILLIAM DUBILIER, OF NEW ROCHELLE, NEW YORK, ASSIGNOR TO DUBILIER
CONDENSER CORPORATION, OF NEW YORK, N. Y., A CORPORATION OF DELAWARE

VARIABLE CONDENSER

Original application filed February 14, 1924, Serial No. 692,864. Divided and this application filed
February 2, 1925. Serial No. 6,375.

My invention relates to condensers, and more particularly to variable condensers of the type used in radio communication.

This application is a division of my application, Serial No. 692,864, filed February 14, 1924 which has matured into Patent 1,722,325.

An object of my invention is to provide a condenser in which gradual adjustments of capacity may be effected with facility and with a minimum of friction of the parts.

Another object of my invention is to provide a variable condenser in which the elements of opposite polarity are immovable, and in which the change of capacity is accomplished by varying the position of another element having no direct electrical connection with the terminals of the condenser.

A further object of my invention is to provide a condenser structure in which the fixed elements are attached to the support in a simple and extremely sturdy manner, whereby the condenser may be subjected to long continued use without fear of injury to the fixed elements.

A still further object of my invention is to provide means for effectively preventing displacement of the flexible element in the operation of the condenser, and also to provide a structure in which the movement of the compression plate for operating the resilient element is limited.

With these and other objects in view which may be incident to my improvements, the invention consists in the parts and combinations to be hereinafter set forth and claimed, with the understanding that the several necessary elements comprising my invention, may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings:

Figure 1 is a top plan view of my variable condenser;

Fig. 2 is a longitudinal sectional view taken on the line 2-2 of Fig. 1, looking in the direction of the arrows;

Fig. 3 is a detail cross sectional view taken on the line 3-3 of Fig. 1, looking in the direction of the arrows.

In my invention, the fixed elements comprise adjacent sheets of metallic foil insulated from each other, and fixed to a suitable insulating support. The sheets of metallic foil are covered by an insulating sheet of mica which extends beyond the edges of the adjacent sheets of foil, forming a projecting overlapping insulating sheet, which prevents possible injury to the edges of the foil.

The adjacent sheets of metallic foil and the mica sheet are held to the support by means of eyelets which are passed through the support, the metallic foil, and the insulating sheet of mica, and are riveted in place to maintain holding washers in firm contact with the mica sheet. The resilient movable element of the condenser comprises a bow, or U-shaped metal strip whose center is adapted to contact against the insulating mica sheet covering the fixed elements. A guiding yoke is attached to the support for the fixed elements, and prevents displacement of the movable element of the condenser. The movable element has no electrical contact with the terminals of the condenser, and the adjacent sheets of metallic foil have no direct electrical connection with each other or with the resilient movable element.

Within the yoke is adapted to move a compression plate against which the ends of the movable element bear. A reciprocable shaft operated by the movement of a screw within an operating knob causes the compression plate to approach or recede from the fixed elements, thereby causing the resilient movable element to be progressively laid down on and picked up from the surface of the fixed elements, thus varying the capacity.

Referring to the drawings for a more detailed description, I have shown an insulating support 1 of bakelite or some other suit-

able insulating material. Fixed to the support 1 at its under side, by some suitable adhesive, are adjacent strips of metallic foil 2 in alinement, and overlying the strips of metallic foil 2, which have no direct electrical connection with each other, is an insulating sheet of mica 3 whose edges project beyond the edges of the strips of foil to protect it from injury (see Figs. 2 and 3). Passing through the support 1, the adjacent strips of metallic foil 2 and the insulating sheet of mica 3 are eyelets 4. The eyelets 4 are inserted through the various layers and holding washers 5 are slipped over the eyelets so that when the eyelets are riveted in place, the holding washers 5 firmly hold the mica sheet 3, which is preferably also adhesively attached to the adjacent strips 2 of metallic foil, against the metallic foil, and the whole against the support 1.

The foil of each element adjacent the eyelets 4 is brought into close electrical contact with the eyelets 4 by turning down sections 2' of the adjacent sheets of foil 2 to contact with the respective eyelets. The washers 5 that hold the condenser elements firmly in place on the supports 1 also serve to tightly hold the adjacent strips of foil in contact with the eyelets. The adjacent strips of metallic foil 2 and the mica sheet 3 comprise the fixed elements of my condenser.

Fastened to the support 1 by means of screws 6, is a yoke 7 of insulating material having downwardly depending parallel sides 8, which project below the fixed element of the condenser. The yoke 7 is formed with a protruding central support 9. The sides 8 have cut out portions 11 therein, which lightens the construction. Passing through the depending parallel sides 8 are stop bars 12, comprising bolts which pass through from one side to the other, and are held in place by means of nuts 13. The stop bars 12 act to limit the movement of the movable element of the condenser in its minimum setting, as will be hereinafter explained.

Adapted to contact at substantially its middle point against the insulating mica sheet 3 covering the adjacent fixed elements 2 of the condenser, is a flexible resilient metallic strip 14, of U, or bow shape. The free ends 15 of the strip 14 bear against and are adapted to slide upon a metallic compression plate 16, which is affixed at substantially its middle by means of a screw 17 to a reciprocable shaft 18. Downward movement of the compression plate 16 is limited by the stop bars 12.

The reciprocable shaft 18 passes through an aperture 19 formed in the resilient metallic strip 14 that operates as the movable element of my condenser. There is an opening 21 formed in the mica strip 3 covering the adjacent fixed elements, and the inner adjacent edges of the fixed elements are

spaced well back from the edges of the opening 21 and out of contact with the shaft 18. The reciprocating shaft 18 passes through an opening 22 formed in the support 1, and an opening 23 formed in the support 9 of the yoke 7.

The support 9 is provided with an annular flange 24. Lying on top of this annular flange 24 is a metallic washer 25 which is depressed at 26 into a depression formed in the upper surface of the support 9. This prevents the washer 25 from rotating. The washer 25 is provided with a tab or lug 27 which fits into a slot 27' formed within the shaft 18 (see dotted lines Fig. 1). The tab 27, by reason of its engaging the slot 27' in the shaft 18, prevents possible rotation of the shaft 18.

Mounted over the support 9 and having its lower surface contacting with the washer 25 is an operating knob 28 of insulating material. The knob 28 is provided with an inner metallic hollow member 29 which is keyed to, or fitted tightly into, the operating knob 28, and is adapted to rotate with the knob. The metallic hollow member 29 is provided with internal screw-threads 31 engaging with screw-threads 32 formed on the reciprocating shaft 18. To hold the operating knob in operative position, I have provided a U-shaped holding piece 33 of resilient metal, which engages the flange 24 formed on the upper end of the support 9, and likewise engages a flange 34 formed on the lower end of the operating knob 28.

The U-shaped holding piece 33 holds the operating knob in operative position. To hold the U-shaped holding piece 33 in place after being fitted over the flanges 24 and 34, I have provided a bolt 35 which passes through the free ends 36. A nut 37 holds the bolt in place and prevents the U-shaped holding member 33 from slipping from the flanges 24 and 34, though it is to be understood that the holding member is not so tightly adjusted as to prevent free rotation of the operating knob 28.

Upon turning the operating knob 28, the screw-threads 31 engage with the screw-threads 32 of the reciprocating shaft 18 and feed the shaft either in an upward or downward direction. The tab 27 on the washer 25, by engaging with the slot 27', prevents possible rotation of the reciprocating shaft 18.

In operation, by turning the operating knob 28, the reciprocable shaft 18 may be raised or lowered to raise or lower the compression plate 16 which causes the resilient U-shaped movable element 14 of the condenser to be laid down on or picked up from contact with the mica sheet 3 covering the fixed elements of the condenser. The capacity is thus varied by flexing the flexible element 14 to vary the amount of capacitative

connection between the adjacent fixed elements of the condenser. As the flexible element 14 comes more and more into contact with the mica sheet 3, the capacity of the device is caused to increase. As the flexible element is picked up from contact with the mica sheet 3, the bridging effect becomes minimized and the capacity of the device falls.

10 While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

15 I claim:—

1. In a variable condenser, an insulating support, adjacent elements each comprising a metallic strip mounted on the support, an insulating sheet over both metallic strips, 25 eyelets passing through the support, the metallic strips and the insulating sheet, and in electrical contact with the metallic strips, and a flexible movable element adapted to be laid down on and picked up from the surface of 30 the insulating sheet, whereby the capacity of the device may be varied.

2. In a variable condenser, an insulating support, adjacent elements each comprising a sheet of metallic foil mounted on the support, an insulating sheet of mica over the said sheets of metallic foil, eyelets passing through the support, the metallic sheet foil and the mica sheet and in electrical connection with the metallic sheet foil, and a resilient movable metallic strip adapted to be 40 laid down on and picked up from the surface of the mica sheet, whereby the capacity of the device may be varied.

3. A variable condenser comprising adjacent fixed elements, a resilient movable element insulated from the fixed elements, a reciprocable shaft having screw-threads thereon, means operated by the shaft to flex the resilient element to vary the capacity of the condenser, an operating knob, and screw-threaded means on the knob to cooperate with the screw-threads on the shaft to reciprocate the shaft.

4. A variable condenser comprising a support, adjacent fixed condenser elements mounted thereon, a U-shaped resilient movable element, a compression plate on which the ends of the movable element bear, a reciprocable shaft passing through the support and attached to the compression plate, screw-means to reciprocate the shaft, a guiding yoke for the movable element fitting over the support and the fixed elements, and means carried by the guiding yoke for limiting the

movement of the compression plate away from the fixed elements.

5. A variable condenser comprising fixed adjacent condenser elements insulated from each other, a resilient movable element adapted to be flexed into proximity to the fixed elements, a guiding yoke for the movable element, and means to limit the movement of the movable element. 70

6. A variable condenser comprising adjacent fixed elements in alignment, a movable element adapted to bridge the fixed elements and to move in a lateral direction relative to the fixed elements to vary the capacity of the condenser, and terminals connected to the fixed elements to connect the condenser in circuit. 75

7. A variable condenser comprising adjacent fixed elements, a flexible movable element bridging the fixed elements and adapted to be flexed in such manner as to vary the capacity of the condenser, and terminals connected to the fixed elements to connect the condenser in circuit. 80

8. A variable condenser comprising adjacent fixed elements, a resilient movable member, a compression plate, a yoke for guiding the movable member, means to flex the resilient movable member to bridge the adjacent elements, and terminals connected to the fixed elements to connect the condenser in circuit. 85

9. A variable condenser comprising adjacent fixed elements in alignment, terminals connected to the fixed elements to connect the condenser in circuit, and an element insulated from the fixed elements and movable toward and from the fixed elements to vary the capacity of the condenser. 90

10. A variable condenser comprising adjacent fixed elements insulated from each other, a movable element insulated from the fixed elements, means for causing the movable element to be laid down on and picked up from the fixed elements to vary the capacity, and terminals connected to the fixed elements to connect the condenser in circuit. 105

11. A variable condenser comprising adjacent fixed elements insulated from each other, a movable element insulated from the fixed elements, a reciprocable shaft for moving the movable element, an operating knob within which the shaft can be reciprocated to vary the capacity of the device, and terminals connected to the fixed elements to connect the condenser in circuit. 110

12. A variable condenser comprising an insulating support carrying fixed elements in alignment, and a movable element mounted to bridge the fixed elements, means to vary the distance between the movable element and the fixed elements to vary the capacity of the condenser, and terminals connected to the fixed elements to connect the condenser in circuit. 115

13. A variable condenser comprising a supporting member of insulation, adjacent elements in alignment secured thereto, a bowed flexible movable element having part 5 of its surface spaced from the fixed elements and part in proximity thereto and adapted to be bent to vary the portion of its surface in proximity to the fixed elements, so that the capacity of the condenser can be varied, and 10 terminals connected to the fixed elements to connect the condenser in circuit.

14. A condenser comprising two fixed spaced plates in a common plane, separate circuit terminals for said plates a third plate 15 movable toward and from said spaced plates, and a layer of dielectric material between said third plate and said two spaced plates, and means for pressing said elements together to vary the distance between them.

20 Signed at New York in the county of New York and State of New York this 31st day of January, A. D. 1925.

WILLIAM DUBILIER.
